(57) **CLAIM**

The ornamental design for an agricultural tape binder, as shown and described.

DESCRIPTION

FIG. 1 is a perspective view showing my new design for an agricultural tape binder,

FIG. 2 is another perspective view thereof,

FIG. 3 is a rear view thereof,

FIG. 4 is a front view thereof,

FIG. 5 is a top view thereof,

FIG. 6 is a bottom view thereof,

FIG. 7 is a right side view thereof; and,

FIG. 8 is a left side view thereof.

The broken lines represent portions of the article and form no part of the claimed design.

1 Claim, 6 Drawing Sheets
